PLASTIC FOAM EAR MUFF

John F. Wall, 499 Midland Ave., Scarborough,
Ontario, Canada

Filed Oct. 13, 1960, Ser. No. 62,481

Term of patent 3½ years

(Cl. D3—13)

FIG. 1

FIG. 3

FIG. 2

FIG. 1 is a perspective view of a plastic foam ear muff, viewed from the top, showing my new design;

FIG. 2 is a perspective view thereof, viewed from the bottom; and

FIG. 3 is a side elevation thereof.

I claim:

The ornamental design for a plastic foam ear muff, substantially as shown.
